DESIGN FOR A BOTTLE

Abraham Lincoln Key, Staten Island, N. Y., assignor to Colgate-Palmolive-Peet Company, Jersey City, N. J., a corporation of Delaware

Application December 29, 1941, Serial No. 104,901

Term of patent 14 years

To all whom it may concern:

Be it known that I, Abraham L. Key, a citizen of the United States, residing at Deere Park, Staten Island, in the county of Richmond and State of New York, have invented a new, original, and ornamental Design for a Bottle, of which the following is a specification, reference being had to the accompanying drawing, forming part thereof.

I claim:
The ornamental design for a bottle, as shown.

ABRAHAM LINCOLN KEY.
